UNITED STATES PATENT OFFICE.

ULYSSES L. BERGER, OF WASHINGTON, DISTRICT OF COLUMBIA.

CURTAIN-BRACKET.

988,852.

Specification of Letters Patent. Patented Apr. 4, 1911.

Application filed September 3, 1910. Serial No. 580,310.

To all whom it may concern:

Be it known that I, ULYSSES L. BERGER, a citizen of the United States of America, residing at Washington, in the District of Columbia, have invented certain new and useful Improvements in Curtain-Brackets, of which the following is a specification, reference being had therein to the accompanying drawing.

10 This invention relates to curtain holders and the principal object of the same is to provide a holder by means of which a curtain can be adjusted vertically for lighting and ventilating purposes, said holder comprising a stationary member that is fastened to a window frame and a curtain carrier that slidably engages said stationary member, means being provided whereby the carrier and member can be locked against relative 15 movement to retain the curtain in the desired position.

In carrying out the objects of the invention generally stated above, it will be understood, of course, that the essential features 20 thereof are necessarily susceptible of changes in details and structural arrangements, preferred and practical embodiments of which are shown in the accompanying drawings, wherein,

25 Figure 1 is a perspective view of a window, the curtain therefor being carried by a pair of the improved adjustable holders. Fig. 2 is a view in front elevation of one of the holders. Fig. 3 is a side view thereof. Fig. 4 is a fragmentary perspective view showing the manner of locking the slide member to the stationary member. Fig. 5 is a similar view showing the slidable connection between said members. Fig. 6 is a 30 transverse sectional view taken on the line 6—6, Fig. 2. Fig. 7 is a similar view taken on the line 7—7, Fig. 4. Fig. 8 is a perspective view of a modified type of stationary member. Fig. 9 is a fragmentary perspective view showing an angular curtain bracket carried by the slide member.

Referring to the accompanying drawings by numerals and particularly to Figs. 1 to 7 thereof, it will be seen that the improved 35 holder comprises a stationary member that is formed of a single length of resilient material, doubled to provide the parallel body members 1, which are spaced to provide a guide slot 2 between the same. The ends of 40 said material are shaped to provide the laterally projecting flat loops 3 which are fas-

tened to the vertical side of a window frame 4. The other end is similarly shaped but obviously provides a single flat loop 5, which is also fastened to the side of the window 40 frame. Adjacent the base loop 5, the body members 1 are crimped toward each other to provide contracted resilient keeper lugs 6, between which the slide member is "snapped" to lock said slide member against longitudinal movement, as will be explained.

The slide member 7 is formed of a single length of resilient material having its lower end rolled to provide a finger grip 8. The upper portion thereof is passed through one 70 end flange 9 of a curtain bracket 10 and transversely crimped to provide flat guide loop 11, and the end thereof is then passed through the upper flange 12 of said bracket 75 and riveted or otherwise rigidly fastened thereto.

In use, the stationary member is fastened to the window frame, and the slide member has its guide loop passed through the slot 2 so that they will slide on the inner surfaces of the members 1 while the bracket 10 is in slidable engagement with the outer surfaces of said members. This prevents lateral movement of the slide member relative 80 to the stationary members, but does not prevent longitudinal movement. It will therefore be seen that the slide member can be adjusted longitudinally of said stationary member, and when the desired adjustment has been obtained, the straight portion of 90 the member 7 is "snapped" past the keeper lugs 6, and thereby clamped against longitudinal movement. The stationary member being resilient, it will be readily apparent 95 that the member 7 can be released from said lugs by an outward pull thereon.

In Fig. 8 a modification of the stationary member is suggested, in which said member is stamped or punched from a single length of resilient sheet metal and shaped to provide the central longitudinally arranged guide slot 13. Said slot has the keeper lugs 14 at the base thereof. The said member, which is designated generally by the numeral 15, has its ends bent outward and flattened to provide the fastening flanges 16, which are similarly arranged and for the same purpose as the end loops of the stationary member of the preferred form of the invention.

It will be seen from the foregoing that in both forms of the invention, simple means

are provided for guiding the slide member and also for locking the same in the desired position.

In Fig. 9, an angular bracket 17 has been shown, the ends of the body 18 thereof being fastened to the slide member 7 in the same manner as that described in the foregoing.

What I claim as my invention is:—

10 1. A curtain holder comprising a stationary member provided with a central longitudinal guide slot, said guide slot provided at the lower portion of its longitudinal edges with oppositely disposed keeper lugs which 15 project toward the center of said slot, and a movable member slideable in said slot and adapted to be "snapped" past said lugs to lock said member against movement.

20 2. A curtain holder comprising a stationary member formed of a single length of resilient material, doubled to provide parallel body members and a central slot, the body members at the base of said slot being

crimped to provide oppositely disposed keeper lugs, the ends of said stationary member provided with laterally projecting fastening loops, and a carrier slidably engaging opposite surface of said body members and adapted to be clamped against movement by said lugs.

30 3. A curtain holder comprising a stationary member provided with a guide slot, a carrier formed of a single length of material having its major portion shaped to provide oppositely projecting loops that extend transversely of one surface of said member, the end of said carrier projecting through said slot, and a curtain support carried by the ends of said carrier.

In testimony whereof I hereunto affix my 40 signature in presence of two witnesses.

ULYSSES L. BERGER.
